ATTORNEY.

UNITED STATES PATENT OFFICE.

CARL SCHEVITZ, OF JACKSONVILLE, FLORIDA.

EXPANSIBLE SHOE-LAST.

1,326,100.

Specification of Letters Patent. Patented Dec. 23, 1919.

Application filed July 18, 1919. Serial No. 311,785.

To all whom it may concern:

Be it known that I, CARL SCHEVITZ, a citizen of the United States, residing at Jacksonville, in the county of Duval and State of Florida, have invented new and useful Improvements in Expansible Shoe-Lasts, of which the following is a specification:

This invention relates to an expansible shoe last provided with means for stretching the shoe, some of said means being movable longitudinally of the last and others laterally of the last.

The present invention is an improvement over that forming the subject matter of the patent granted to me on December 31, 1918, No. 1,289,927.

The principal object of the present invention is to provide means whereby the various adjustments of the stretching members may be made from the exterior of the shoe so that it is not necessary to place the hand in the shoe to adjust the members.

The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Fig. 1 is an elevation of the invention.

Fig. 2 is a longitudinal section thereof.

Fig. 3 is a section on line 3—3 of Fig. 1.

Fig. 4 is a detail view of the locking means for the sliding frames.

Fig. 5 is a detail sectional view showing the means for adjusting the toe stretching member.

Fig. 6 is a view of the toe stretching member.

Fig. 7 is a view of the side stretching member.

Fig. 8 is a view partly broken away, of the instep support.

Fig. 9 is a plan view of a portion of this support.

Fig. 10 is a perspective view of one of the sliding frames.

Fig. 11 is a perspective view of one of the cam frames.

In these views 1 indicates the main frame which has each side thereof provided with a pair of slots 2. At the rear of the main frame is secured the lower end of the upright 3. Within the main frame is located 60 a pair of longitudinally extending strips 4, said strips being spaced apart and at their front ends having upwardly extending portions 5 which are notched as at 6. These strips form a guideway for the longitudinally movable bar 7 which passes through an opening in the front cross piece of the main frame. The front end of said bar is provided with a spring pressed pin 8 and this end is adapted to receive the toe stretching member 9. The rear end of this bar is provided with a screw threaded bore 10 which receives the screw threaded part of shaft 11. This shaft is connected with the upright shaft 12 by the gears 13. The shaft 12 is carried by lugs 14 formed on the upright 3. The upper end of the shaft 12 is square so as to receive the squared socket of the key 15.

Associated with the main frame is the heel frame 16 which is of substantially U-shape, with the under edges of the legs of the U provided with a plurality of notches 17 and the upper edges at the ends of the leg provided with the projections 18. These notches and projections are adapted to engage the projections 19 on the upright 3 to permit the adjustment of said heel frame. The heel frame is also provided with the handle 20.

The above arrangement of parts is substantially similar to that described in the before mentioned patent.

A pair of sliding frames 21 are located in the spaces between the sides of the frame and the strips 4. These side frames are of yoke-shape and are each provided with a small laterally extending lug 22 at the extremity of one leg and an upwardly extending part 23 at the extremity of the other leg. Each leg is also provided with a pair of elongated slots 24 which are adapted to register with the slots 2 in the main frame and with similar slots in the strips 4. The lugs 22 are also adapted to engage with the slots 2 in the main frame.

A pair of cam frames 25 are located in the frames 21 and both sets of frames are slidingly held in the main frame by the pins 26, a pair of which is carried by each 110

of the cam frames, having their ends engaging the slots 24 in the frames 21 and the slots in the main frame and strips 4.

As shown in Fig. 11 the cam frames are 5 of channel shape in cross section with one end closed and this closed end has an inclined corner 27, which forms a cam. This closed end of each cam frame is adapted to coöperate with the closed end of the frame 10 21 for adjusting the side stretching member 28.

The upwardly projecting part 23 of each of the frames 21 has pivoted thereto a rack bar 29 the teeth of which are adapted to engage 15 a cross piece 30, which forms part of a channel bracket 31 secured to the upright 3. As shown in Fig. 4 the rack bars engage slots formed in the upper edge of said cross piece 30.

20 The rack bars are adapted to be held with their teeth engaging the cross piece by means of a rod 32 carrying a pin 33, which engages the upper edges of said rack bars, and said rod is provided with a guide 34 25 at its lower end which has sliding engagement with the bracket 31. The rod 32 is normally held with its pin in engagement with the rack bars by a spring 35. The upper end of the spring bears against a 30 collar 36 loosely mounted on the rod and having its upper end engaging the bent over end 3' of the upright 3. The rod 36 passes through a keyhole-shaped opening in said bent end and the rod is provided with a 35 flat portion for engaging the small part of this opening so as to hold the rod in its upper position, against the tension of the spring and with the pin 33 out of engagement with the rack bars to permit said bars 40 to be moved longitudinally so as to adjust the frames 21.

A pair of curved arms 37 is connected with the rear part of the main frame by the links 38 and the front ends of these arms 45 are pivotally connected to the cam frames 25 by pins 39 passing through the reduced portions 40 of said cam frames. The upper ends of the arms are pivotally connected to the socket members 41 and these socket 50 members receive the ends of the screw threaded shafts 42 which pass through the screw threaded collars 43. Said collars are held against rotation in the part 3' of the upright 3. The upper ends of the shafts 55 42 are squared to receive the key 15.

An arm 44 is pivotally mounted to the bracket 45 which extends forwardly from the upright 3 and the front end of the said arm carrying a roller 46 which is adapted 60 to engage the underface of the instep support 47. This arm is rocked above its pivotal point by means of the shaft 47 having a squared portion engaging a screw threaded socket carried by the bracket 45 and having 65 its upper end passing through the part 3'

and provided with a squared portion to receive the key 15. This shaft is provided with a collar 48 for engaging the arm 44 to move the roller on said arm upwardly against the instep support to stretch the instep of the shoe. This support is provided with a pin 47' for engaging the slots 6 in the projections 5.

The operation of the device is as follows:—

The last is placed within the shoe and the heel frame adjusted to make the last fit the shoe. The key is then placed on the shaft 12 and the same rotated to force the toe stretching means 9 into the toe. The 80 key is then placed on shaft 47 to move the arm 44 to adjust the instep support to stretch the instep. Then the key is placed on one of the shafts 42, according to which side the side stretching member 28 is located. 85 By raising the rod 32 the rack bars are unlocked and by rotating the shaft by the key both the cam frame and the side frame can be adjusted longitudinally to place the side stretching member 28 in its proper position. 90 The frame 21 is locked by lowering the rod 12 so that upon further rotation of the shaft the cam frame will move within the frame 21 and thus press the shank 48' of the side stretching member 28 between the ends of 95 the two frames and the pressure of the cam 27 against the inclined face of the shank will cause said member 28 to move laterally away from the side of the main frame.

It will thus be seen that the whole adjustment may be carried out from the exterior of the shoe so that it is not necessary to place the hands within the shoe.

When the locking rod 32 is in raised position the guide 34 will be raised so as to hold the rack bars above the cross piece 30 and thus permit free movement of the frames 21.

It is thought from the foregoing description that the advantages and novel features 110 of my invention will be readily apparent.

I desire it to be understood that I may make changes in the construction and in the combination and arrangement of the several parts; provided that such changes fall 115 within the scope of the appended claims.

What I claim is:—

1. In an expandible shoe last, a main frame, a side stretching member carried thereby and means operated from the exterior of the shoe for moving said member longitudinally and laterally in relation to the frame.

2. In an expandible shoe last, a main frame, a side stretching member carried thereby and means operated from the exterior of the shoe for moving said member longitudinally and laterally in relation to the main frame, said means including a slidible frame located in the main frame, a cam 130

frame located in said sliding frame and having its cam engaging an inclined part on the side stretching member, a vertical shaft adapted to be moved vertically from the exterior of the shoe and means for connecting said shaft with the main frame.

3. In an expansible shoe last, a main frame, a sliding frame fitting therein, a cam frame fitting in the sliding frame, means connected with the cam frame for moving the same from the exterior of the shoe, means for locking the sliding frame against movement from the exterior of the shoe and a side stretching member actuated by the movement of said cam frame.

4. In an expansible shoe last, a main frame having slots therein, a yoke frame slidably mounted in said main frame and having slots therein registering with the slots in the main frame, a cam frame located in said yoke frame, pins on said cam frame extending through the slots, a side stretching member having its shank passing through one of the slots in each of the main and yoke frames, and having an inclined part thereon engaged by the cam of the cam

frame, an arm pivoted to the main frame and having one end secured to the cam frame, a vertically movable shaft connected with the other end of said arm, a vertically movable rod and means associated with said rod for locking the yoke frame against movement.

5. In an expansible shoe last, a main frame, a toe stretching member, a longitudinally movable bar connected with said member, means for moving said bar including an upright shaft, a side stretching member, means for adjusting the same both longitudinally and laterally, said means including an upright shaft, locking means for holding the longitudinal adjusting means of the side stretching member stationary, said locking means including an upright rod, an instep support, means for adjusting the same, such means including an upright shaft, all of said shafts and rod being adapted to extend through the top of the shoe and a key adapted to engage the upper ends of the shaft for operating the same.

In testimony whereof I affix my signature.
CARL SCHEVITZ.
